MACHINE FOR CEMENT-ATTACHING
WELTING

John R. Oliver, Beverly, Mass., assignor to United
Shoe Machinery Corporation, Flemington,
N. J., a corporation of New Jersey

Application December 23, 1940, Serial No. 371,268

37 Claims. (Cl. 12—51)

This invention relates to a machine for attaching a welting strip to a shoe and, as illustrated herein, is directed more specifically to a machine for adhesively uniting a precoated welting strip to the outturned flange of a shoe.

In one method of shoemaking the upper material, including the upper and lining, is thread-lasted to a middle sole of canvas or similar material. The surplus of the flange formed thereby is then trimmed off close to the bottom of the shoe at an angle to provide an abbreviated outwardly directed flange to which the welting may be attached. It is for adhesively attaching a welting to the flange of this type of shoe that the machine of the present invention is designed, and it is an object of the invention to provide for rapid, accurate application of the welting to the flange in such a manner as to insure an enduring bond between the welting and flange.

The narrow surfaces of the flange and welting strip afford very little bonding area. Consequently, both surfaces are precoated with cement, the upper surface of the flange being roughed before the application of cement thereto to remove the finished grain surface to which cement will not adhere perfectly. The cement applied to the beveled flange is extended over the lasting thread and thread holes to avail of all possible bonding area. Consequently, to take advantage of this and in order to insure proper adhesion between the flange and welting, care must be taken to press the precoated inner or apex edge of the beveled portion of the welting well up into the crease between the flange and upper.

In accordance with the practice described in application Serial No. 350,493, filed August 3, 1940, in the name of Fred L. Ayers, the welting and flange are progressively adhesively united by a pair of feed rolls, a portion of one of the feed rolls being adapted to project into the crease between the flange and upper. The novel features of the present invention reside in means associated with one of the feed rolls for guiding the welting over the roll with its inner edge coincident with the aforesaid portion so that the inner edge of the welting is forced into the crease between the flange and upper, and means on the other roll raised above the surface thereof and adapted to project into the crease between the flange and bottom.

While the operation may be performed with facility along the sides of the shoe, the contour at the toe is such that the welting crinkles and does not lie flat in the crease. Accordingly, an-

other feature of the invention resides in the combination in a machine of this character of means for progressively pressing the welting into engagement with the flange of the shoe and means for forming slashes in that portion of the welting which will surround the toe of the shoe before it is applied to the shoe so that when attached it will lie flat in the crease between the flange and upper.

When the welting has been laid completely about the shoe, it is desirable to sever the attached portion from the unattached portion. Consequently, another feature of the invention lies in the combination in a machine of this character of means for severing the welting and of means for supporting the welting during the severing operation so that it will not be pushed aside without being cut.

In order to prevent damage to the shoe when the welting is severed, for example, by contact of the severing knife with the upper, the operator generally draws off an appreciable length of welting before he severs the same. Because of this, a considerable length of welting projects from the feed rolls which must be moved back between the rolls if it is to be acted upon by the feed rolls to press it onto the flange when the succeeding shoe is presented to the feed rolls. This is effected in the present machine by means for retracting the unattached welting a sufficient distance after it has been severed so that its free end is substantially at the bite of the feed rolls.

The objects of the present invention having been described generally, the specific construction and operation will now be described in detail with reference to the drawings, in which

Fig. 1 is a side elevation of the machine;
Fig. 2 is a detail of the welting guide;

Fig. 3 is an enlarged view showing the flange and welting held in engagement by the feed rolls;
Fig. 4 is a plan view of Fig. 1, partly in section;

Fig. 5 is a front elevation showing the slasher mechanism;

Fig. 6 is an angular view of the welting cutter and gripper;

Fig. 7 is a plan view of the welting retracting means;

Fig. 8 is a fragmentary view showing the feed rolls in engagement with the flange and welting;

Fig. 9 is a detail of the drive for the upper feed roll;

Fig. 10 shows the cam for driving the cutter and gripper; and

Fig. 11 shows a one-revolution clutch for connecting the driven shaft with the cam.

The illustrated machine comprises a pair of feed rolls 10 and 12 which are constructed and arranged progressively to press a precoated welting strip W against the precoated surface of the bottom flange F of a shoe S (Fig. 3) and into the crease between the flange and the upper, a slasher 14 (Fig. 5) for slashing that portion of the welting strip which is to extend about the toe of the shoe, a severing knife 16 (Fig. 6), and a gripper 18 for holding the welting strip during the severing operation, and a retractor 20 (Fig. 1) for pulling back the free end of the unattached severed welting so that at the beginning of each operation the free end of the welting will be substantially at the bite of the rolls 10 and 12.

The feed rolls 10 and 12 are mounted on a head 22 which is tilted at an angle of approximately 35° to the horizontal on the upper end of a supporting column 24. The angular position of the head brings the feed rolls 10 and 12 into a convenient position for the operator. The lower roll 10 serves not only as a feed roll but also as a support and presser roll and is provided with a frusto-conical surface and the work-engaging portion thereof occupies a substantially horizontal plane so that the lower face of the flange F of the shoe rests against this surface with the shoe tilted at an angle, as illustrated in Fig. 1, thereby permitting the operator to have a clear view of the progress of the welting W as it is applied to the flange. The large end of the roll 10 terminates in a peripheral bead 10' (Fig. 3) which projects upwardly from the frusto-conical surface thereof for a purpose which will appear hereinafter. The roll 10 is fixed to a shaft 26 which is journaled in an arm 28 pivotally supported at 30 in the head 22. A sprocket 32 is fixed to the inner end of the shaft 26 by which the shaft, and consequently the roll 10, may be driven, as will appear hereinafter. The upper feed roll 12 serves as an abutment over which the welting travels and against the resistance of which the roll 10 holds the shoe with its flange F pressed into engagement (Figs. 3 and 8) with the beveled surface of the welting W, and to this end, the roll 12 is provided with a frusto-conical surface (Fig. 9) the work-contacting portion of which is substantially parallel to the co-operating portion of the frusto-conical surface of the roll 10, the larger end of the roll 12 being arranged so that it projects into the crease between the flange and the upper to guide and force the inner or apex edge of the welting as far as possible into this crease. When the rolls are in operative position (Fig. 8) the bead 10' on the roll 10 projects into the crease between the flange and bottom along the thread line of the inseam. The crest of the bead acts partly as a guide, and because it lies in the plane of the end of the roll 12, it also insures an unyielding pressure between the flange and welting at the innermost edge of the welting. The roll 12 is journaled in a bracket 12' (Fig. 4) fixed to the end of an arm 34 which, in turn, is fixed at its inner end to the face of the head 22 substantially parallel to the arm 28, and is driven from a shaft 34' housed in the arm 34 by means of gears 35 and 35' (Fig. 9). The shaft 34' has fixed to its inner end a sprocket 36 (Fig. 1) which is connected with the sprocket 32 by a chain 36' whereby the rolls 10 and 12 rotate together and in opposite directions. The shaft 34' is driven from a constantly rotating shaft 160 by means of meshing gears 162 and 164, the former being fixed

to the shaft 160 and the latter being fixed to the shaft 34' (Fig. 1).

In order to grip the work and forcibly to press the flange into engagement with the welting, the lower roll 10 is normally urged toward the roll 12 by means of a spring 41, the distance between the rolls in operative position being fixed by means of a stop 38 (Fig. 1) mounted on the fixed arm 34, the end of the stop abutting the arm 28. This distance may be varied by adjustment of the stop 38. A treadle rod 40 is provided for lowering the roll 10 so that the work may be placed between the rolls, and to this end, the rod is attached to an arm 42 fixed to the arm 28 and extending rearwardly thereof whereby the arm 28 may be tilted about its pivot 30.

The welting W which has been previously coated with adhesive along its beveled edge is supplied from a reel (not shown) and led vertically downward therefrom to the entrance side of the feed rolls 10 and 12, the free end e of the welting extending between the rolls and being held substantially taut by the same, as illustrated in Fig. 5. The welting is guided over the surface of the roll 12 by means of guides 43 and 45 (Figs. 2 and 8). The guide 43 holds the welting against the peripheral surface of the roll 12 and is provided with a finger 43' parallel to the end of the roll which engages the inner or apex edge of the welting and prevents it from riding off the large end of the roll. The guide 43 is adjustably mounted at 47 (Fig. 8) and may be moved transversely of the surface of the roll 12 in accordance with the width of the welting. The guide 45 (Fig. 2) substantially conforms to the surface of the roll 12 and is disposed adjacent to the lower side thereof (Fig. 8). A projector 44' extends upwardly around the front side of the roll and serves to facilitate introduction of the welting between the guide and roll. The guide 45 is provided with a tooth 45' which projects toward the surface of the roll at the small end and is adapted to engage the outer square edge of the welting to hold the welting with the inner or apex edge of its beveled portion in coincidence with that portion of the edge of the roll 12 which projects into the crease between the flange and upper. The guide 45 is also adjustable widthwise of the roll to accommodate different widths of welting, being held in position by a screw 44' (Fig. 8).

Heretofore, when welting has been applied to a shoe, it has been necessary to slash it obliquely and to beat it after it was attached in order to straighten it so that it would be in the proper position for the application of the sole thereto. It has been found, however, that when the welting is slashed throughout its entire length that portion of the welting which extends along substantially straight runs of the shoe appears to be somewhat ragged. Around the toe and any other sharp bends, this raggedness is not as noticeable, due to the fact that longitudinal stretching of the welting at these points tends to close the slashes so that they do not show. In order to eliminate this ragged appearance along the straight portions of the shoe, it is proposed to slash the welting only along that portion thereof which is to surround the toe of the shoe and to leave the remainder of the welting unslashed. To this end, a slasher 14 (Fig. 5) is provided in the present machine which may be brought into operation at such a time during the application of the welting to the shoe that only that portion of the welting which is to surround the toe will be slashed. The slasher 14 consists of a two-bladed cutter 44 fixed to the

end of a shaft 46 which is journaled in an arm 48 pivotally mounted at 50 on a bracket 52 bolted to the head 22. A pulley 54 is fixed to the end of the shaft 46 and is constantly rotated by means of a belt 56 which is connected with a pulley 118 (Fig. 4). A knee-operated rod 58 is secured to the arm 48 at 60 and provides means for tilting the arm 48 in a clockwise direction about its pivot 50 to bring the cutter 44 into engagement with the flesh or beveled side of the welting. The cutter in its active position lies in a plane at substantially 45° to the plane of the welting so that the slashes are at approximately 45° to the surface of the welting. A spring (not shown) normally returns the cutter and the arm 48 to an inoperative position. The depth of slash made by the cutter may be varied by limiting the downward movement of the arm 48. This is accomplished by providing a boss 48' on the back of the arm 48 to which there is fixed a pin 49'. The free end of the pin 49' co-operates with a slot 49 formed in a bracket 51. A screw 51' at the end of the slot limits the downward movement of the pin 49' in the slot.

The unsupported length of welting between the source of supply and the feed rolls is so flexible that means must be provided for holding it during the slashing operation and, consequently, a combined guide and support 68 (Fig. 5) is provided. The guide and support 68 forms a part of the bracket 51 which is screwed to the end of the arm 34. The guide and support is provided with a vertically extending passage 70 through which the welting passes on its way to the feed rolls. An angular slot 72 (Fig. 1) is formed in one wall of the passage 70 for the reception of the ends of the cutter blades as they slash the welting.

As is evident, the slashing operation is carried out during the application of the welting to the shoe but before the slashed portion of the welting is applied to the shoe. Due to variation in the sizes of shoes, it is impractical to employ gaging means for determining when to begin the slashing operation and when to end it in order to obtain slashing along that portion of the welt which is to surround the toe. It has been found, however, by experiment, that the proper slashing can be obtained for any size shoe by bringing the slashing knife into operation at about the same time that the welting is being pressed into engagement with the ball of the shoe and continuing the slashing until the welting has been applied to a point just short of the toe of the shoe, whereupon the slashing should be discontinued. If the slashing is carried out during this period of application of the welting, the slashed length will coincide with the toe portion of the shoe. Sometimes it happens that an especially deep shank is employed in a shoe. When this is so, it is desirable to slash the welting so that it will lie flat along the bend between the shank and ball. This may be accomplished by bringing the slasher into operation a little past the breast line and continuing it to a point about half way out of the shank.

After the welting has been applied about the entire shank and forepart of the shoe from breast line to breast line, the attached welting must be severed from the unattached portion of the welting. To this end, a reciprocating knife 16 (Figs. 4 and 6) is provided. When the welting is to be cut, the operator normally pulls the shoe away from the feed rolls to the left in Fig. 1, a substantial distance so that a free length of welting will be exposed for severing, and also to remove the

shoe from the range of the end of the knife so that the upper will not be damaged. This free length of welting must be supported during the cutting operation and, consequently, a gripper 18 is provided for gripping the welting adjacent to the cutter and holding it during the cutting operation.

The gripper 18 is mounted for reciprocation to and from the welting on a line parallel to the axis 10 of the roll 10 and is supported by a web 14 formed integral with the arm 34 (Fig. 6). The gripper comprises a pair of jaws 76 and 78 (Fig. 6), the jaw 76 being fixed to a slide 80 which is mounted in a dovetail groove 82 formed in the web 14. A gib 74' forms one side of the dovetail groove and is screwed to the web at 75. The jaw 78 is pivotally mounted at 81 on the slide 80 and the reciprocation and closing of the jaws are accomplished as follows: the inner end of the slide 80 is connected by means of a link 84 (Fig. 1) to a lever 86 which is, in turn, connected to a lever 88 the free end of which is provided with a cam roll 90 which occupies a cam groove 92 formed in one face of a cam 94 (Fig. 10). The lower jaw 78 is connected by means of a rod 96 to the end of the lever 86. When the cam is rotated, the counterclockwise motion of the lever 86, as seen in Fig. 1, at first gives a forward motion to the slide 80 so as to move the jaws toward the welting strip. As the slide moves forward, the link 84 is turned about the end of the slide 80 as a center and the proportions of the link are such that when the gripper moves into the plane of the welting, the rod 96 will be moved forward to close the lower jaw. In this position the link 84 is substantially in line with the slide 80 on a dead center so that the jaws are locked in position. The cam track 92 is so formed that the jaws remain locked during the cutting operation, which will be described hereinafter, and thereafter are released and withdrawn for a subsequent operation.

The knife 16 (Fig. 6) is reciprocated in a manner similar to the gripper 18 and consists of a bar 100 beveled at its outer end to provide a cutting edge, the bar being slidably mounted in a dovetail groove 102 formed in the outer surface of the slide 80 so that it slides with the jaws to and from the welting strip. To provide for further movement of the knife, that is, cutting movement during the time the jaws are gripping the welting, the inner end of the bar 100 is connected by means of a link 104 and a lever 106 to a lever 108 (Fig. 4), the latter being connected to a lever 110 having a cam roll 112 at its free end which rides in a groove 114 formed in the opposite face of the cam 94. The lever 106 is pivoted at 106' on the end of the bar 100 and is slidably connected to the lever 108 by a pin 116 and groove 116' so that during the initial forward movement of the gripper 18 the knife 16 remains inoperative. When the gripper has moved forward far enough to grip the welting, the cam 94 begins to turn the lever 108 in a counterclockwise direction, as seen in Fig. 1, which, in turn, moves the lever 106 in a clockwise direction so as to force the bar 100 forward and thereby passes the cutting edge of the knife through the welting strip. The cam track is so formed that the knife is immediately withdrawn to a position for a subsequent operation. The gripper 18 and knife 16, as described above, are operated by the cam 94 (Fig. 10) which is intermittently driven by a one-revolution clutch 115 (Fig. 11) connecting it with the hub of the constantly rotating pulley 118. The pulley 118 is fixed to a shaft 166 which is driven

from the shaft 160 by a pair of bevel gears 168 and 170 (Fig. 4). The cam 94 is mounted to turn freely on the shaft 166 and may be connected to the hub of the pulley by a spring-pressed pin 115' which is housed in a recess 117 formed in the hub of the cam. A recess 117' is formed in the hub of the pulley, and when the recesses 117 and 117' are opposite, the end of the pin 115' is pressed into the recess 117', thereby connecting the pulley and cam. A nub 119 is fixed to the pin 115' and extends from the hub of the cam through a slot 119'. The pin 115' is withdrawn from the recess 117' by means of a cam 121 which is fixed to a bar 120' which may be moved into the path of the nub 119 by means of the treadle 120. When the treadle is depressed, the cam 121 is moved out of the path of the nub 119 and the pin 115' snaps into the recess 117, thereby locking the hub of the pulley to the hub of the cam. Upon release of the treadle 120 the cam 121 is moved into the path of the nub 119 and as the nub moves into engagement with the cam 121 the pin 115' is withdrawn from the recess 117' to disengage the drive between the pulley 118 and cam 94. To prevent overdrive by reason of momentum of the cam 94, a spring-pressed brake 122 (Fig. 4) is mounted in a boss 124 formed on the head 22 which is adapted yieldably to engage the peripheral surface of the cam 94. The braking action may be increased or decreased by adjusting a screw 126.

As heretofore indicated, when the welting has been severed, a substantial length thereof projects from the forward side of the feed rolls. If this projecting piece is not retracted when another shoe is presented to the rolls, the free end *e* of the welting will not be pressed by the rolls into engagement with the flange of the shoe and will consequently constitute a waste end which must be cut off. To eliminate such waste and to insure the proper adhesion of the leading or free end of the welting and the flange, it is desirable to draw the welding back between the rolls 10 and 12 so that its free end *e* is substantially at the bite of the rolls in position to have the flange pressed into engagement therewith (Fig. 5). To this end, a retractor 20 is provided which consists of a pair of jaws 126 and 128 (Fig. 7) which are disposed in open position on opposite sides of the welting above the slasher, as shown in Fig. 1. The jaws are carried by an arm 130 which is pivotally supported at 132 on a bifurcated stud 134 projecting from the top side of the arm 34. The arm 130 is connected (Figs. 1 and 5) by members 136, 138, 140 and 142 to the treadle rod 120 by means of which the arm 130, and consequently the retractor 20, may be moved a predetermined distance along the welting *W*. The distance through which the retractor 20 is moved along the welting is equal to the length of welting which will normally be drawn off by the operator when he severs the attached welting from the unattached welting. Consequently, when the retractor 20 is moved downwardly along the welting by means of the treadle rod 120 and is caused to grip the welting, as will be hereinafter described, and is then released so that it moves back to its original position, it will retract the welting so that the free end *e* thereof will occupy a position substantially at the bite of the feed rolls. The retractor 20 is normally held in its inoperative position by means of a light spring 146 surrounding the link 138 with its ends abutting a collar 146' fixed to the link 138 and the end of the member 140, the latter being movable longitudinally of the link

138. By depressing the treadle rod 120, the jaws 126 and 128 (Fig. 7) are brought down into gripping position. If the treadle is immediately released, the jaws will remain in their gripping position and the member 140 will merely compress the light spring 146. As soon as the welting is cut, however, the spring 146 will return the retractor 20 and the welting to their initial positions. The jaw 126 is fixed and the jaw 128 is pivotally mounted on the arm 130 at 148. The pivoted jaw 128 is moved into and out of gripping relation with the jaw 126 by a cam 150 which is screwed to the end of a bracket 152, the latter being fixed to the top side of the arm 34. The cam 150 consists of a hollow frame having an irregular track 154, shown in Figs. 4 and 6, with one side or the other of which the tail end 156 of the movable jaw 128 is held in engagement by a spring-pressed beveled pin 158. As the retractor 20 is moved downwardly along the welting, the tail end of the jaw 128 moves downwardly along the left-hand side of the track, being held in engagement therewith by the spring-pressed pin 158. At the lower end of the track the jaw 128 is moved by the inwardly directed portion of the track about its pivot point to close against the jaw 126. The spring-pressed pin 158 is mounted in the arm 130 and projects into the path of the tail end 156 of the jaw 128 so that as the jaw is biased to a closed position the tail end of the jaw is moved past the spring-pressed pin 158 and is held thereby against the right-hand side of the track. When the treadle 120 is released and after the welting has been severed, the gripper 20 moves upwardly along the cam track 154 and, as it approaches the top, the inwardly directed portion of the track moves the tail end 156 of the jaw 128 to the opposite side of the spring-pressed pin 158, thereby releasing the welting and holding the jaw in an open position.

To apply the welting to the flange of the shoe, the operator separates the feed rolls by raising the treadle rod 40 and rests the flange of the shoe on the depressed roll 10 and then releases the treadle rod 40 so that the upper surface of the flange is brought squarely into contact with the beveled edge of the welting which lies around the periphery of the presser roll 12, as illustrated in Fig. 1. The rotation of these rolls carries forward the work, which the operator must guide, making sure that the apex of the welting is pressed as far as possible into the groove between the flange and upper. When the work progresses to the point where the welting is being applied to the ball, the operator then depresses the knee-operated rod 58 for bringing the slasher 14 into operation and holds this rod down until a point short of the toe of the shoe is reached, whereupon he releases the rod. The operator continues to guide the shoe between the rolls until the welting is laid completely around the shoe from breast line to breast line. In order to sever the attached welting from the unattached welting, the operator pulls the shoe away from the feed rolls a short distance, so as to expose a short length of welting, and then actuates the treadle rod 120 which cocks the retractor 20 and by the rotation of the cam 94 simultaneously brings the gripper 18 and severing knife 16 into operation. As soon as the welting is severed, the spring 146 returns the retractor 20 to its initial position, thereby withdrawing the welting so that the free end thereof is substantially at the bite of the

rolls so that it will be in proper position for application to the next shoe presented.

Having described my invention, what I claim as new and desire to secure by Letters Patent of the United States is:

1. A machine for adhesively attaching strip welting to a shoe having an outturned flange, comprising means for progressively uniting a precoated welting strip with the flange, said means consisting of a support for the welting strip, a portion of said support being adapted to project into the crease between the flange and upper, means for guiding said welting over the support with its inner edge coinciding with the aforesaid portion, a support for the flange, means on said last-named support raised above the surface thereof adapted to project into the crease between the flange and bottom, and means for yieldably urging the support for the flange in toward the support for the welting to press said flange against said welting.

2. A machine for adhesively attaching strip welting to a shoe having a thread-lasted outturned flange, comprising means for progressively uniting a precoated welting strip with the flange, said means consisting of a pair of co-operating feed rolls, one of said rolls having an edge projecting into the crease between the flange and upper, guides associated with the last-named feed roll for guiding the welting around its peripheral surface with its inner edge coinciding with the edge of the roll, a bead on the other roll raised above the surface thereof for engagement with the thread line between the flange and the bottom, and means for bringing said rolls into co-operating relation to press said flange into engagement with the welting.

3. A machine for adhesively attaching strip welting to a shoe having an outturned flange, comprising means for progressively uniting a precoated welting strip with the flange, said means consisting of a pair of co-operable feed rolls, one of said rolls having an edge adapted to fit into the crease between the flange and the upper, the other of said rolls having a raised bead on its peripheral surface opposite said edge of the first-named roll and projecting toward the same, said bead being adapted to fit into the crease between the flange and bottom, means for bringing the rolls together to press the flange and welting into engagement, and means for rotating said rolls.

4. A machine for adhesively attaching strip welting to a shoe having an outturned flange, comprising co-operable feed rolls for progressively uniting a precoated welting strip with the flange, said rolls being frusto-conical, the surfaces of said rolls at their line of contact with the work being substantially parallel, and a raised peripheral bead on the large end of one of said rolls, the crest of said bead projecting toward the large end of the other roll and being positioned on the machine to contact with the shoe substantially in the plane of the end of said other roll.

5. A machine for attaching strip welting to a shoe having an outturned flange, comprising means constructed and arranged progressively to press the flange of the shoe against a precoated welting strip thereby adhesively to unite the welting to the shoe, means associated with the first-named means to guide the unattached welting to a position to be acted upon by the first-named means, and means for slashing a portion of the unattached welting while the welting is being pressed into engagement with the flange.

6. A machine for attaching strip welting to a shoe having an outturned flange, comprising means constructed and arranged progressively to press the flange of a shoe against a precoated welting strip thereby adhesively to unite the welting to the shoe, means associated with the first-named means to guide the unattached welting into a position to be acted upon by the first-named means, means for slashing a predetermined length of the unattached welting, and means for moving said slashing means into and out of operation at will.

7. A machine for attaching welting to a shoe having an outturned flange, comprising means constructed and arranged progressively to press the flange of the shoe against a precoated welting thereby adhesively to unite the welting to the shoe, means associated with the first-named means to guide the unattached welting into a position to be acted upon by the first-named means, means for forming slashes in a portion of the unattached welting before it is pressed into engagement with the flange, and means for adjusting the position of the slashing means to vary the depth of the slashes.

8. A machine for attaching a welting strip to a shoe having an outturned flange, comprising means constructed and arranged progressively to press the flange of the shoe against a precoated welting thereby to form an enduring bond between the flange and welting, means associated with the first-named means to guide the unattached welting into a position to be acted upon by the first-named means, means for supporting the unattached welting at one point in advance of the guide means as it is guided to the shoe, and means for slashing said welting at its point of support.

9. A machine for adhesively attaching a welting strip to a shoe having an outturned flange, comprising welting feeding means constructed and arranged progressively to press the flange of the shoe against a precoated welting strip thereby permanently to fix said welting to said flange, a constantly rotating blade for forming oblique slashes in the surface of the welting, and means for moving said blade into the path of the welting.

10. A machine for attaching a welt to a shoe having an outturned flange, comprising means constructed and arranged progressively to press the flange of the shoe against a precoated welting strip, a rotary blade disposed at an angle to the surface of the welting for slashing the same, a support and guide through which the welting passes at the point of slashing, and means for moving said rotary blade into and out of slashing position.

11. In a machine for progressively adhesively attaching welting to a shoe having an outturned flange, feeding means constructed and arranged progressively to press the flange of the shoe against a precoated welting strip thereby permanently to fix said welting to said flange, a support for a portion of the welting not in engagement with the shoe and a rotary cutter movable into contact with the surface of the welting at its point of support for forming slashes in the welting.

12. In a machine for progressively adhesively attaching welting to a shoe having an outturned flange, feeding means constructed and arranged progressively to press the flange of the shoe against a precoated welting strip thereby perma-

nently to fix said welting to said flange, a combined support and guide for a portion of the welting not in engagement with the shoe, a constantly rotating two-bladed cutter movable into contact with the surface of the welting at its point of support for forming slashes in the welting, and means for moving said cutter into and out of operation.

13. In a machine for progressively adhesively attaching welting to a shoe having an outturned flange, a support for the welting, a rotary multi-bladed cutter movable into contact with the surface of the welting at its point of support for forming slashes in the welting, and means for varying the depth of the slashes.

14. A machine for attaching welting to a shoe having an outturned flange, comprising means constructed and arranged progressively to press the flange of the shoe against a precoated welting strip thereby adhesively to unite the welting to the shoe, means associated with the flange-pressing means for guiding the unattached welting into a position to be acted upon thereby, and means for severing the attached welting from the unattached portion of the welting strip.

15. A machine for attaching a welting to a shoe having an outturned flange, comprising means for supporting the flange, means for supporting a precoated welting strip, means for urging said flange supporting means toward said welting supporting means thereby adhesively to unite the flange and welting, means associated with the flange-pressing means for guiding the unattached welting into a position to be acted upon thereby, means for severing the attached welting from the unattached portion of the welting strip, and means for moving said severing means into and out of position.

16. A machine for attaching a welting strip to a shoe having an inturned flange, comprising means constructed and arranged progressively and adhesively to unite the flange of the shoe with a welting strip, means associated with the flange-pressing means for guiding the unattached welting into a position to be acted upon thereby, and means for severing the attached welting from the unattached portion of the welting strip, said means comprising a knife reciprocable in a line intersecting the path of the welting, said knife being disposed laterally of the means for uniting the welting with the flange.

17. A machine for adhesively attaching a precoated welting strip to a shoe having an outturned flange, comprising a pair of co-operating rolls constructed and arranged progressively to press the flange of the shoe against a welting strip, means for severing the attached welting strip from the unattached portion of the welting strip, and means for supporting said welting during the severing.

18. A machine for attaching a welting strip to a shoe having an outturned flange, comprising a pair of co-operating rolls constructed and arranged progressively to press the flange of the shoe against a precoated welting thereby adhesively to unite the flange and welting, means for severing the attached welting from the unattached portion of the welting strip, and means to support said welting adjacent to the point of severance for preventing lateral movement of the welting during the severing.

19. A machine for attaching a welting to a shoe having an outturned flange, comprising a pair of co-operating rolls constructed and ar-

ranged progressively to press the flange of the shoe against a precoated welting thereby adhesively to unite the flange and welting, means for severing the attached welting from the unattached portion of the welting strip, means for supporting said welting during severance, and means for moving said supporting means into operative position prior to the actuation of the welting severing means.

20. A machine for attaching a welting to a shoe having an outturned flange, comprising a pair of co-operating rolls constructed and arranged progressively to press the flange of the shoe against a precoated welting thereby adhesively to unite the flange and welting, means for severing the attached welting from the unattached portion of the welting strip, gripper means for supporting said welting during severance, means for moving said supporting means into welt gripping position, and means for locking said gripper means during the actuation of said welting severing means.

21. A machine for attaching a welting strip to a shoe having an outturned flange, comprising a pair of co-operating welting feed rolls constructed and arranged progressively to press the flange of the shoe against a precoated welting whereby the welting and flange are adhesively united, a pair of grippers, means for moving said grippers across the path of the welting, means for closing said grippers to grip the welting, and means for severing said welting while gripped by said grippers.

22. A machine for attaching a welting strip to a shoe having an outturned flange, comprising a pair of co-operating rolls constructed and arranged progressively to press the flange of the shoe against a precoated welting whereby the welting and flange are adhesively united, reciprocable means for severing the attached welting from the unattached portion of the welting strip, reciprocable means for supporting the welting during severance, and common means for reciprocating said supporting means and said severing means.

23. In a machine for progressively adhesively attaching a welting strip to a shoe having an outturned flange, a welting severing knife reciprocable across the path of the welting, and a gripper reciprocable in a direction parallel to the reciprocation of the knife and in advance thereof, said gripper being adapted to grip and hold the unattached portion of the welting during severance.

24. In a machine for progressively adhesively attaching a welting strip to a shoe having an outturned flange, a welting severing knife, a gripper for holding the welting during severance, a reciprocable bar for moving the gripper into and out of welting holding position, means on said bar for supporting said knife for reciprocation with the gripper, and means for reciprocating said bar.

25. In a machine for progressively adhesively attaching a welting strip to a shoe having an outturned flange, a welting severing knife, a gripper for holding the welting during severance, a reciprocable bar for moving the gripper into and out of welting holding position, means for slidably supporting said knife on the bar for reciprocation with the gripper, reciprocating means connected to the bar for reciprocating the gripper,

and means for reciprocating the knife with relation to the gripper.

26. In a machine for progressively adhesively attaching a welting strip to a shoe having an outturned flange, a welting severing knife, a gripper for holding the welting during severance, a reciprocable bar for moving the gripper into and out of welting holding position, a groove in said bar for slidably receiving said knife, and a driven cam a portion of which serves to reciprocate the bar and another portion of which serves to reciprocate the knife relative to the bar.

27. A machine for adhesively attaching a pre-coated welting strip to a shoe having an outturned flange, comprising a pair of co-operating rolls constructed and arranged progressively to press the flange of the shoe against a welting, means for severing the attached welting from the unattached portion of the welting strip adjacent to the rolls, and means for pulling the projecting free end of the unattached welting back substantially to the bite of the rolls.

28. A machine for adhesively attaching a pre-coated welting strip to a shoe having an outturned flange, comprising a pair of co-operating rolls constructed and arranged progressively to press the flange of the shoe against a welting, means for severing the attached welting from the unattached portion of the welting strip adjacent to the rolls, and a pair of jaws operable to grip the unattached welting and to draw the free end thereof backwardly between the rolls.

29. A machine for adhesively attaching a welting strip to a shoe having an outturned flange, comprising a pair of co-operating rolls for feeding the welting strip, said rolls being constructed and arranged progressively to press the flange of the shoe against a welting strip, means for severing the attached welting from the unattached portion of the welting strip adjacent to the rolls, a pair of jaws lying on opposite sides of the path of movement of the welting, means for causing said jaws to grip the unattached welting, and means for moving said jaws in a direction opposite to the normal movement of the welting to retract the free end of the unattached welting a predetermined distance.

30. A machine for adhesively attaching a pre-coated welting strip to a shoe having an outturned flange, comprising a pair of co-operating rolls constructed and arranged progressively to press the flange of the shoe against a welting strip, means for severing the attached welting from the unattached portion of the welting strip adjacent to the rolls, a pair of jaws operable to grip the welting, means for causing the jaws to grip the welting, means for moving the jaws to retract the welting, and means for causing said jaws to release the welting at the end of the retraction.

31. A machine for adhesively attaching a pre-coated welting strip to a shoe having an outturned flange, comprising a pair of co-operating rolls constructed and arranged progressively to press the flange of the shoe against a welting strip, means for severing the attached welting from the unattached portion of the welting strip, a pair of jaws operable to grip the welting, a cam for causing the jaws to grip the welting, and means for moving the jaws to retract the welting, said cam causing said jaws to release the welting at the end of the retraction.

32. In a machine for progressively adhesively

attaching a precoated welting strip to a shoe having an outturned flange, a welting severing knife for severing the attached welting from the unattached portion of the welting strip, a pair of jaws operable to grip the welting, a cam for causing said jaws to grip the welting, and means for moving the jaws to retract the welting, said cam causing said jaws to release the welting at the end of the retraction.

10 33. A machine for attaching a welting strip to a shoe having an outturned flange, comprising means constructed and arranged progressively to press the flange of the shoe against a pre-coated welting strip, a guide for directing the welting to the pressing means, means for forming slashes in the surface of the welting as it passes through said guide, and means for severing the attached welt from the unattached portion of the welting strip.

15 34. A machine for adhesively attaching a welting strip to a shoe having an outturned flange, comprising means constructed and arranged progressively to press the flange of the shoe against a welting strip, means for slashing the welting along that portion thereof which extends around the toe, means for severing the attached welting from the unattached portion of said welting strip, and means for supporting said welting during the severing operation.

20 35. A machine for adhesively attaching a welting strip to a shoe having an outturned flange, comprising a pair of co-operating rolls constructed and arranged progressively to press the flange of the shoe against a welting strip, means for slashing a predetermined length of the welting for application about the toe, means for severing the attached welting from the unattached portion of the welting strip, and means for moving the severed unattached welting strip backward a predetermined distance.

25 36. A machine for adhesively attaching a welting strip to a shoe having an outturned flange, comprising means constructed and arranged progressively to press the flange of the shoe against a welting, means for slashing a predetermined length of welting for application about the toe, means for severing the attached welting from the unattached portion of the welting strip, means for holding the welting during the severance thereof, and means for retracting the severed unattached welting strip a predetermined distance.

30 37. A machine for adhesively attaching strip welting to a shoe having an outturned flange, comprising feed rolls for progressively uniting a precoated welting and the flange, said rolls being frusto-conical, the large ends of said rolls projecting into the grooves between the flange and upper and between the flange and bottom of the shoe, a guide spaced from the peripheral surface of one of the rolls holding the welting in contact with said surface, said guide having a flange projecting toward said surface and parallel to the large end of the roll for engagement with one edge of the welting, and a guide disposed opposite the peripheral surface of the same roll adjacent to the lower side thereof, said guide conforming substantially to the surface of the roll and having a finger projecting toward the surface at the small end of the roll to engage the other edge of the welting and being adjustable widthwise of the roll.

JOHN R. OLIVER.
